BOBBIN WITH TAIL-TIE

John Wale and Alexander G. Edgington, Coventry, England, assignors to Courtaulds Limited, London, England, a British company

Application January 30, 1953, Serial No. 334,284

5 Claims. (Cl. 242—125)

This invention relates to bobbins particularly for use in collecting artificial threads.

In one continuous method of manufacture of viscose thread, viscose is extruded from a jet into a coagulating bath and the resulting thread is passed through various liquid treatment stages before being dried and wound on to a bobbin. Owing to the speed at which thread is delivered to the bobbin, the handling of the thread during bobbin changing and rethreading to a new bobbin may present difficulties to the operator, especially when a ring-spindle is used for winding. The threading-up difficulties are increased when it is desired to secure the leading end of the thread to the bobbin, separate from the main winding, to form a tail. It is known to use an air suction tube to take up a travelling thread during threading-up operations. For example, in United States of America Patent No. 2,485,776, a bobbin mounted on a twisting machine has a chamber within the bore which is connected with a vacuum pump through a hollow spindle. The base of the chamber is fitted with a screen so that a travelling thread led to the chamber is drawn in and retained within the chamber. When the bobbin is rotated, the operator leads the thread into an external groove on the upper part of the bobbin for the purpose of winding a tail and then leads the thread on to the barrel of the bobbin for the normal winding operation.

The object of the present invention is to facilitate securing a tail to a bobbin.

According to the present invention, a bobbin has a thread trap within the bore for the purpose of securing a tail, the thread trap being capable of catching and holding a thread passing through the bore when the bobbin is rotated at the commencement of a winding operation.

In a preferred form of the invention, the thread trap comprises a horizontal spring strip secured at one end to the wall of the bore of the bobbin, the other end curving inwards towards the axis of the bore to form a guiding surface to the nip between the strip and the wall of the bore.

In an alternative form of the invention, the thread trap comprises a spiral spring or a spring ring which is mounted in an annular groove within the bore of the bobbin and is held in the groove by the outward pressure of the spring. The inner end of the spring forms a guiding surface to the nip between the spring and the wall of the bore of the bobbin.

In one method of securing a tail to the bobbin containing spring strips according to the invention, the bobbin is mounted on a ring spindle having a suction tube passing up the bore of the bobbin to a point below the thread trap. A travelling thread is fed into the suction tube, and is then threaded into the traveller on the ring. The upper edge of the suction tube is fitted with a cutting edge which is capable of severing the thread when the thread is drawn into contact with it. When the bobbin is rotated, the thread passing from the traveller to the bobbin is directed on to the barrel of the bobbin and

2

winding proceeds in the normal manner. The thread passing down the bore of the bobbin is caught by the free end of the spring strip and is guided by the strip into the nip between the strip and the wall of the bore, where it is held. The thread in the bore is now brought into contact with the cutting edge on the suction tube where it is severed leaving a tail secured by the thread trap.

Specific examples of bobbins constructed in accordance with the present invention are illustrated in the accompanying drawings, in which—

Figure 1 is a front elevation partly in section, showing a bobbin mounted on a ring-spindle prior to winding a thread on the bobbin,

Figure 2 is a perspective view on a larger scale of the end of the suction tube shown in Figure 1,

Figure 3 is a fragmentary view, on a larger scale, of Figure 1 when winding has just commenced,

Figure 4 is a plan view of Figure 3,

Figure 5 is a fragmentary front elevation in section of a further form of bobbin in accordance with the invention, and

Figure 6 is a plan view of Figure 5.

In Figure 1, a bobbin 1 is mounted on a platform 2, rotatable by a spindle motor 3, of a ring spindle indicated generally at 4. The motor 3 is mounted on a traverse rail 5, and a tube 6 passes centrally through the motor 3, the platform 2 and part of the way up the bore 7 of the bobbin 1. The tube 6 is connected to an air suction apparatus (not shown) and traverses with the rail 5. Within the bore 7, a horizontal spring strip 12 is secured at one end by a screw 13 to the wall of the bore 7, between the top of the bobbin 1 and the top of the tube 6. The other end of the strip 12 curves away from the wall of the bore 7 towards the axis of the bore 7.

The end of the tube 6, as shown in Figure 2, is provided with a serrated thread cutting edge 14 extending over about half the circumference of the tube 6. The remaining half of the circumference of the tube 6, shown at 15, is smooth.

To set up a travelling thread 8 passing downwards from a drying reel of a continuous spinning machine (not shown) through a guide 9, the thread 8 is led by hand into the bore 7 of the stationary bobbin 1 where it is drawn into the tube 6. The thread 8 is then looped through a traveller 10 on a fixed ring 11 as shown.

The bobbin 1 is now rotated to begin the winding operation and the thread 8 passing between the traveller 10 and the bobbin 1 is caused to wind on the bobbin 1 in the normal manner as is shown in Figure 3 so that the looped thread is overwound by winding 16. Simultaneously, the thread 8 in the bore 7 is caught in the nip 17 between the strip 12 and the wall of the bore 7, the thread 8 being guided into the nip by the curved strip 12 by virtue of the direction of rotation of the bobbin 1 (shown by an arrow in Figure 4). The thread 8 is securely trapped by the nip 17 and is also brought into contact with the cutting edge 14 of the tube 6 so that after several revolutions of the bobbin 1, the thread 8 is severed at the point where it enters the tube 6.

Winding the thread on to the bobbin 1 proceeds until the bobbin is full when it is stopped and the full bobbin replaced by an empty bobbin. The thread 8 secured within the nip 17 constitutes a tail and may be used in the known manner for joining up to another bobbin during an unwinding operation. Setting up of the fresh bobbin is then effected as described above.

A further form of bobbin is shown in Figures 5 and 6 where the strip 12 is replaced by a spring ring 18 which fits into an annular groove 19 in the bore 7 of the bobbin 1 and is retained in this position by the outward pressure of the spring 18.

The spring 18 has an inner end 20 which curves towards the axis of the bore 7 and acts in the same manner as the strip 12 in catching and guiding the thread 8 into a nip 21 between the spring 18 and the wall of the bore 7 when the bobbin is rotated in the direction of the arrow, as shown in Figure 6.

The end 20 of the spring 18 is preferably tilted in the upward direction so as to facilitate the catching of the thread 8.

What we claim is:

1. A bobbin for the collection of threads comprising a cylindrical barrel upon the outer surface of which the threads are wound, there being a cylindrical bore passing longitudinally through the center of the barrel, and a curved member totally enclosed within the bore, one end of the curved member being held associated with the wall of the bore while a remaining part of the member curves away from the wall toward the axis of the bore in such manner that a nip is defined between the member and the wall at a point intermediate the ends of the bore and in a direction adapted to catch and hold as a tail a thread passing through the bore when the bobbin is rotated for winding at the commencement of winding.

2. A bobbin according to claim 1 in which the curved member is at such a level inside the bore and below the top thereof that when the bobbin is mounted on a ring spindle having a suction tube passing up the bore of the bobbin with cutting means on the upper edge of the tube, the curved member is adapted to hold the thread in contact with the cutting means.

3. A bobbin as claimed in claim 1 wherein the end of the curved member which curves from the wall of the bore is also tilted upwardly to facilitate catching the thread.

4. A bobbin for the collection of threads comprising a cylindrical barrel upon the outer surface of which the threads are wound, a cylindrical bore passing longitudinally through the centre of the barrel and a spring strip located within the bore, one end of the spring strip being secured to the wall of the bore and the other end of the spring strip curving from the wall of the bore towards the axis of the bore so defining a nip between the spring and the wall of the bore for the purpose of catching and holding as a tail, a thread passing through the bore when the bobbin is rotated at the commencement of a winding operation.

5. A bobbin for the collection of threads comprising a cylindrical barrel upon the outer surface of which the threads are wound, a cylindrical bore passing longitudinally through the centre of the barrel and a spring ring located in an annular groove within the wall of the bore, one end of the spring ring being held against the wall of the bore by outward pressure of the spring ring and the other end of the spring ring curving from the wall of the bore towards the axis of the bore so defining a nip between the spring and the wall of the bore for the purpose of catching and holding as a tail, a thread passing through the bore when the bobbin is rotated at the commencement of a winding operation.
